UNITED STATES PATENT OFFICE.

WILLIAM P. PITTS, OF KANSAS CITY, MISSOURI, ASSIGNOR TO IRVING-PITT MANUFACTURING COMPANY, OF KANSAS CITY, MISSOURI, A CORPORATION OF MISSOURI.

TEMPORARY BINDER.

Application filed March 28, 1921. Serial No. 456,175.

To all whom it may concern:

Be it known that I, WILLIAM P. Pitt, a citizen of the United States, residing at Kansas City, in the county of Jackson and 5 State of Missouri, have invented a certain new and useful Improvement in Temporary Binders, of which the following is a specification.

My invention relates to improvements in 10 temporary binders. It is particularly adapted for use in connection with binders of the type having posts telescopically fitted and attached to two leaf embracing members. One of the objects of my invention is to 15 provide a binder of the kind described, which is cheap to make, easy to operate, durable, not liable to get out of order, which may be cheaply bound with canvas or other binding material, which will reliably hold 20 the leaf embracing members from moving outwardly from any position within their range of movement, which will present an attractive appearance and which is efficient in operation.

25 A further object of my invention is to provide a novel extensible lock for connecting the post-supporting members, which will not require notching of the corners of the loose leaves, which will occupy small space 30 and that located in the marginal portion at the outer edges of the leaves, which will hold the binding material on the post-supporting members, and which may be attached to the post-supporting members after 35 the binding has been applied thereto, which may be quickly and easily locked and unlocked and which has means for being reliably held in either the locked or the unlocked position.

40 My invention provides further a novel post-supporting member which can be cheaply bound and which eliminates expensive hand binding and which has novel means for attachment to a cover.

45 The novel features of my invention are hereinafter fully described and claimed.

In the accompanying drawings, which illustrate the preferred embodiment of my invention,

50 Fig. 1 is a perspective view, partly broken away, of a binder provided with my improvement.

55 Fig. 2 is an enlarged plan view, partly broken away, with the covers in the open position.

Fig. 3 is an enlarged view of the binder shown partly in plan, partly in longitudinal section and partly broken away.

Fig. 4 is a perspective view of the two angle plates shown separated from each other.

Fig. 5 is an elevation, partly broken away, of one side of the improved binder.

Fig. 6 is a similar view of the other side of the binder. 65

Fig. 7 is a view similar to Fig. 5, the adjacent lock being shown partly in vertical section, the cam being shown in the locking position.

Fig. 8 is a view similar to Fig. 7, the cam 70 being shown in the unlocked position.

Fig. 9 is a vertical sectional view enlarged on the line 9—9 of Fig. 3.

Fig. 10 is an enlarged longitudinal vertical section through one of the end locks and 75 parts connected therewith.

Fig. 11 is a perspective view of one of the 80 slidable members of one of the end locks.

Fig. 12 is a perspective view of the other 85 slidable member of one of the end locks.

Similar reference characters designate 90 similar parts in the different views.

1 and 2 designate respectively two right-angled plates, each having secured to it inwardly extending posts 3, adapted to be slidably fitted in tubular posts 4, attached to the other member. The flange of each plate 1 and 2, Fig. 4, to which the posts are attached has one longitudinal edge formed into barrels 5, adapted to receive a pintle 6, which 95 is mounted in the adjacent edge of an adjacent cover 7.

Each member 1 and 2 is embraced on both sides and all its edges by a sheet of binding material 8. 100

The post-supporting members 1 and 2 are adapted to embrace loose leaves 9, Fig. 1, which are mounted in the usual manner on the posts 3 and 4.

For releasably holding the leaf embracing members 1 and 2, from outward movement, from any point within their range of movement, I provide two end locks, which are extensible and which connect the members 1 and 2 adjacent their ends respectively. 105

The two end locks are similar in construction so that a description of one will suffice for both.

Each end lock comprises two members 10 and 11, the member 10 being provided on 110

its outer side with longitudinal parallel flanges 12, respectively slidably fitted in two longitudinal channels 13, provided on the inner side of the outer member 11. One end of the member 10 is provided with a channel portion 14, which embraces the adjacent end and the inner and outer side of the post supporting member 1, see Figs. 1, and 5 to 12.

10 One end of the member 11 is provided with a channel portion 15, which embraces the adjacent end and the inner and outer sides of the flange of the member 2, which supports the posts 3 and 4.

15 The channel portions 14 and 15 are fitted over the binding 8, after the latter has been applied to the members 1 and 2, thereby protecting the binding material and holding it in position. After the channel portions 14 and 15 have been applied to the plates 1 and 2, they may be firmly fastened thereto by punching indentations 16, Figs. 1 and 10, which indentations enter holes 17 respectively, which are provided in each end 25 of each plate 1 and 2, see Fig. 4, and Fig. 10.

Extending inwardly from each plate 11 is a horizontal pin 18, on which is pivoted a cam 19, Figs. 5 to 8, which has a wedge shaped projection 20, adapted to engage 30 with the adjacent flange 12, as shown in Figs. 5 to 7, at any point within the range of movement of the member 10, and in a manner such that any outward movement of the member 10, will tend to force the projection 20 between the pin 18 and the flange 12, and thus wedging the cam 19 tightly 35 against the flange 12, thereby locking the members 10 and 11 against outward movement. The projection 20 is arranged to engage 40 the flange 12 at the inner side of a transverse plane intersecting horizontally the pin 18. By means of this construction, the cam 19 permits the members 10 and 11 to be forced inwardly but holds them from 45 moving outwardly from any point, when the cam 19 is in the locking position shown in Figs. 5 to 7.

For manually swinging the cam 19 to and from the locking position, it is provided 50 with a finger hold 21, which extends outwardly through a slot 22, in the plate 11.

55 Preferably the cams 19 are, for convenience in manipulating, both arranged on the members 11, so as to be swung in the same direction to the locking position, that is, toward the covers 7. To release the cam 19, the finger holds 21 are both swung away from the covers 7, to the position shown in Fig. 8, in which position the projections 20 will be respectively released from engagement 60 with the adjacent flanges 12.

For reliably holding the cam 19 in either the locked position shown in Fig. 7 or in the unlocked position shown in Fig. 8, there 65 is provided a spring 23, one end of which

is attached to the plate 11, and the other end of which is attached to the adjacent cam 19, the arrangement being such that the pressure of the spring 23 will be toward the pin 18, and such that when the cam 19 is moved from the unlocked position shown in Fig. 8 to the locked position shown in Fig. 7, or in the reverse direction, the end of the spring which is attached to the cam will cross a straight line connecting the center of the pin 18 with the point on the plate 11, at which the spring is attached to the plate 11. By means of this construction, the spring 23 is double-acting and will releasably hold the cam 19 in either 70 the locked or the unlocked position.

One of the flanges 12 of the member 10 is provided at its inner end with a projection 24, Fig. 11, which projection, after the parts have been assembled, as shown in Figs. 5 to 9, is bent to the right, as shown in Figs. 7 and 8, so as to engage the projection 20 of the cam 19, when the latter is in either the locked or the unlocked position. If the member 10 is drawn outwardly, a sufficient 80 distance, the projection 24 will engage the projection 20 of the adjacent cam 19 and will swing the latter to the locked position, shown in Fig. 7, thus preventing the members 10 from being accidentally withdrawn 85 from the members 11. This will occur at a point in which the telescoping posts 3 and 4 will still be engaged with each other. The binder will thus be held by the cams 19 from being opened to a position in which 90 leaves can become accidentally detached from the posts 3 and 4.

In the construction of the binder and the assembling of the parts thereof, the strips of binding material are folded over and glued to the sides and all of the edges of the angle plates 1 and 2, which is a simple 105 operation and which eliminates expensive hand manipulation. The posts 3 are then slipped into the posts 4, after which the channel portions 14 and 15 of the members 10 and 11 are respectively forced onto the adjacent ends of the angle plates 1 and 2 and over the binding material 8 thereon. A punch is then used to force indentations 110 16 into the holes 17 from the channel portions 14 and 15, thus securely holding the plates 10 and 11 rigidly fastened to the members 1 and 2, without any other attaching means. The pintles 6 are then engaged with the barrels 5 and covers 7, thereby 115 completing the assembling of the binder.

In the operation of the binder, the finger holds 21 are both swung from the locking position shown in Figs. 5 to 7, to the unlocked position shown in Fig. 8, after which the members 10 and 11 are pulled outwardly 120 to the open position, after which the leaves 9 having the usual edge slits, not shown are slipped onto the posts 4 and 3.

The finger holds 21 are then swung toward the covers 7 to the locking position shown in Figs. 5 to 7, after which the members 10 and 11 are forced toward each other until 5 the leaves 9 are clamped together by the members 1 and 2. The locking cams 19 will hold the members 1 and 2 in the clamping position, from which position the members 1 and 2 may be released by first swinging the 10 finger holds 21 to the release position and then drawing the members 10 and 11 outwardly.

It will be noted that between the side edges of the leaves 9 and the side edges of 15 the covers 7 and the end edges of the members 1 and 2, there are clear marginal portions 23, Figs. 1 and 2, such as are usually provided between the edges of the leaves and the covers of a book, and that the locks are 20 located wholly within these marginal portions respectively, thus eliminating the necessity of notching the corners of the loose leaves 9.

I do not limit my invention to the structure shown and described, as many modifications, within the scope of the appended claims, may be made without departing from the spirit of my invention.

What I claim is:—

- 30 1. In a binder of the kind described, two leaf-embracing members, and an extensible lock connecting said members comprising two members slidable one on the other and respectively attached to said leaf-embracing members, a locking member carried by one of the slidable members and movable to and from a position in which it will lockingly engage the other slidable member, and means cooperating with said locking member to hold the leaf-embracing members from moving outwardly from any point while permitting them to move inwardly, substantially as set forth.
- 35 2. In a binder of the kind described, two leaf-embracing members, and an extensible lock connecting said members comprising two members slidable one on the other respectively attached to said leaf-embracing members, a locking member carried by one of the slidable members and movable to and from a position in which it will lockingly engage the other slidable member, and a spring arranged to hold the locking member in either the locked or unlocked position, substantially as set forth.
- 40 3. In a binder of the kind described, two leaf-embracing members, and an extensible lock connecting said members comprising two members slidable one on the other respectively attached to said leaf-embracing members, and a locking cam pivoted to one of said slidable members and movable into and out of locked engagement with the other slidable member, substantially as set forth.
- 45 4. In a binder of the kind described, two leaf-embracing members, and an extensible lock connecting said members comprising two members slidable one on the other respectively attached to said leaf-embracing members, a locking cam carried by one of the slidable members and movable into and out of locked engagement with the other slidable member, and a spring arranged to hold the cam in the locking or the unlocked position, substantially as set forth.
- 50 5. In a binder of the kind described, two leaf-embracing members, and an extensible lock connecting said members comprising two members slidable one on the other respectively attached to said leaf-embracing members, a locking cam pivoted to one of the slidable members and movable to and from locked engagement with the other slidable member, and a spring arranged to hold the cam in either the unlocked or the locked position, substantially as set forth.
- 55 6. In a binder of the kind described, two leaf-embracing members, and an extensible lock connecting said members comprising two members slidable one in the other respectively attached to said leaf-embracing members, and a locking cam pivoted to the outer slidable member and movable to and from locked engagement with the inner slidable member, the cam being arranged to hold the slidable members from outward movement but permitting their inward movement, substantially as set forth.
- 60 7. In a binder of the kind described, two leaf-embracing members, and an extensible lock connecting said members comprising two members slidable one in the other respectively attached to said leaf-embracing members, the outer slidable member having a slot, and a locking cam pivoted to the outer slidable member at the inner side thereof and having a finger hold extending through said slot and movable to and from locked engagement with the inner slidable member, substantially as set forth.
- 65 8. In a binder of the kind described, two leaf-embracing members, each having leaf-engaging posts telescopically engaging the posts of the other member, and an extensible lock comprising two members slidable one on the other respectively attached to said leaf-embracing members, a locking member carried by one of the slidable members and movable to and from a position in which it will lockingly engage the other slidable member and arranged when in the locked position to hold said slidable members from moving outwardly from any position while permitting their inward movement, and means cooperating with said locking member in either the locked or unlocked position to hold the slidable members from moving to a position in which the telescoping posts will be detached from each other, substantially as set forth.

- 4
9. In a binder of the kind described, two leaf-embracing members, each comprising a plate and a strip of binding material embracing the sides and edges of the plate, 5 and two extensible end locks comprising each two members, one slideable on the other respectively embracing said plates and the binding strips thereon, and releasable means connecting said slideable members for holding them from outward movement from any point, substantially as set forth. 10
10. In a binder of the kind described, two leaf-embracing members, each comprising a plate and a strip of binding material embracing the sides and edges of the plate, 15 and two extensible end locks arranged to hold said members from outward movement from any position, each end lock embracing said plates and the strips of binding material thereon, substantially as set forth. 20
11. In a binder of the kind described, two leaf-embracing members, each having leaf-engaging posts respectively telescopically engaging the posts of the other member, and 25 two extensible end locks arranged to hold said members from outward movement, each of said locks having portions embracing the inner and outer sides and the adjacent ends respectively of said members, substantially as set forth. 30
12. In a binder of the kind described, two leaf-embracing members, and an extensible lock comprising two members slideable one on the other, said slideable members having 35 portions respectively embracing the inner and outer sides of said leaf-embracing members respectively, and releasable means for locking said slideable members against outward movement, substantially as set forth. 40
13. In a binder of the kind described, two leaf-embracing members, and two extensible end locks, each comprising two members slideable one on the other, each slideable member embracing the inner and outer sides of 45 the adjacent leaf-embracing member, and releasable means for locking said two slideable members against outward movement, substantially as set forth. 50
14. In a binder of the kind described, two leaf-embracing members, and two independently operated end locks, each comprising two members slideable one on the other, each slideable member embracing the inner and 55 outer sides of the adjacent leaf-embracing member, and means independent of the other lock for releasably holding the two slideable members from outward movement, substantially as set forth. 60
15. In a binder of the kind described, two leaf-embracing members, and two extensible end locks connecting said members adjacent to the respective ends thereof, each end lock comprising two members, one slideable on the other, and a locking cam pivoted to one of the slideable members and having a finger hold and movable to and from a position in which it will have locked engagement with the other slideable member and arranged when locked to hold said slideable members at any point from outward movement, said finger holds being movable in like directions when the cams are moved toward the locking position, and means for normally swinging said cam toward the locking position, substantially as set forth. 70
16. In a binder of the kind described, two leaf-embracing members, and two extensible end locks connecting said members adjacent to the respective ends thereof, each end lock comprising two members, one slideable on the other, a locking cam pivoted to one of the slideable members and movable independently of the other cam of the other lock to and from a position in which it will lockingly engage the other slideable member for holding the slideable members against outward movement, and a spring arranged and adapted to force the cam to the locking position, substantially as set forth. 75
17. In a binder of the kind described, two leaf-embracing members, and two extensible end locks connecting said members adjacent to the respective ends thereof, each end lock comprising two members, one slideable on the other, respectively attached to the leaf-embracing members, and a cam pivoted to one of said slideable members and movable to and from a position in which it will engage and hold the other slideable member against outward movement, and a spring arranged to hold the cam in either the locked or in the unlocked position, substantially as set forth. 80
- In testimony whereof I have signed my name to this specification.
- WILLIAM P. PITTS.
